PIVOTED TYPE HEAD FOR TOY TYPEWRITER
 Edwin I. Berger, 460 Redmond Road, South Orange, N.J.
 Filed Dec. 28, 1960, Ser. No. 79,002
 5 Claims. (Cl. 197—47)

It is among the objects of the invention to provide a pivoted type head for a toy typewriter that is simple in construction, using substantially solely sheet metal stock and is not likely to become deranged, that may readily be operated and permits ready shifting of the type head for typing of upper and lower case letters with relatively simplified mechanism.

According to the invention these objects are accomplished by the arrangement and combination of elements hereinafter described and particularly recited in the claims.

In the accompanying drawings in which is shown one of various possible embodiments of the several features of the invention,

FIG. 1 is a transverse sectional view showing the type wheel in position to imprint lower case letter,

FIG. 2 is a view similar to FIG. 1 showing the type wheel in position to imprint upper case letters,

FIG. 3 is a perspective view of the mechanism to effect shifting of the type head from lower case to upper case position,

FIG. 4 is a sectional view taken along line 4—4 of FIG. 3, and

FIG. 5 is a detailed sectional view taken along line 5—5 of FIG. 3.

Referring now to the drawings, the pivoted type head is incorporated in a toy typewriter which may be of the general type shown in Patent No. 2,905,300 and co-pending application Serial No. 812,686, filed May 12, 1959, now Patent No. 2,964,156.

The toy typewriter has an inclined platform or base 11 to the rear of which a platen structure 12 is slidably mounted. As such platen structure may be of the type shown in said co-pending application and per se forms no part of the present invention, it will not be described in detail.

Mounted on the platform 11 centrally aligned with the carriage base 13 of the platen 12 is a support 15, preferably comprising a substantially rectangular base 16 having a pair of upstanding transversely aligned arms 17, 18 at opposite ends on each side thereof and a pair of transversely aligned upstanding arms 19 on each side respectively adjacent the arms 18.

Pivoted on the aligned pair of arms 19 is a U-shaped key lever 21, depression of which effects the typing operation by the means hereinafter described. The arms 22 of the key lever 21 are pivoted between their ends on upstanding arms 19 as by rivets 23. Pivoted at one end to the free end of each of the arms 22 is a link 24, the other end of which is pivoted as at 25 to the obliquely extending arms 26 of a substantially U-shaped sheet metal carriage 27, said pivotal connection 25 being between the ends of such obliquely extending arms 26. The free ends of the obliquely extending arms 26 are pivotally connected to the upstanding arms 17 as by rivets 28, said rivets extending through oblique slots 29 in the upstanding arms 17 to provide a pivotal and slideable mount for the ends of such arms.

Also pivotally mounted by said rivets 28 are the ends of the arms 31 of a U-shaped locking member 32, said arms straddling the upstanding arms 19. The locking member 32 has a cross piece 33 extending transversely across the base 16 and adapted to abut against a shoulder 34 formed on the sides of each of the arms 19 adjacent the arms 18.

The length of the arms 31 and the distance between the shoulders 34 and the lower end of slot 29 is such that when the cross piece 33 abuts against the shoulders 34, the arms 31 will retain the pivots or rivets 28 at the lower end of slots 29.

Rotatably mounted on an axle 41 extending at right angles to the cross piece 42 of carriage 27 is a type wheel 43 having at its periphery two rows of type heads, the upper row comprising lower case letters and numbers and the lower row comprising upper case letters and numbers. As is clearly shown in FIGS. 1 and 2, the periphery of the type wheel 43 extends beyond the cross piece 42 of carriage 27 so that when such carriage is rotated in the manner hereinafter described, one of the letters or numerals on either the upper or lower row will strike against the ribbon 44 aligned with the platen 12 to cause a corresponding impression to be made on the sheet of paper 45.

The key lever 21 is connected through a suitable linkage with an escapement mechanism 46 of suitable type, such as that shown in the above-identified patent application, which will advance the platen 12 one space with each depression of the key lever 21. The linkage desirably comprises a rod 47 extending transversely across the base and rotatably mounted in arms 18, one end of said rod being bent at substantially right angles to carry a spacer key 48.

Secured to said rod 47 is a curved lever 49, the free end of which coacts with the cross piece 51 of the key lever 21. The lever 49 has a finger 52 which is connected by link 53 to actuator arm 54 of the escapement mechanism 46. As such escapement mechanism and the actuator arm 54 are under spring tension, the lever 49 will normally be urged in a counterclockwise direction, referring to FIG. 4.

The U-shaped locking member 32 is freely mounted on pivots 28. Hence the cross piece 33 thereof will normally drop by gravity to its downward rest position as shown in FIGS. 1 and 4. Normally, when the key lever 21 is not pressed, the cross piece 33 will be positioned to the rear of the shoulder 34 so that the pivotal axis 28 of the carriage 27 will be at the lower end of inclined slot 29.

Means are provided to move the cross piece 33 of locking member 32 clear of shoulder 34. To this end, a lever 56 is provided pivotally mounted adjacent one end on the end of rod 47. The lever 56 extends parallel to the arms 31 of locking member 32 and has a hook conformation 57 at its free end which engages the underside of arm 31 between its ends. The other end of lever 56 has a finger 58 rising therefrom which mounts a shift key 59 at its upper end.

The lever is so mounted on rod 47 that when the key 59 is pressed to pivot the lever 56 in a clockwise direction from the position shown in FIG. 1 to the position shown in FIG. 2, the arm 31 will be pivoted sufficiently so that the cross piece 33 is clear of shoulder 34.

The operation of the typewriter may be briefly summarized. With a sheet of paper 45 inserted between the platen 12 and the elongated ribbon 44, the type wheel 43 is rotated so that the desired character or numeral is aligned with the ribbon. Assuming that a lower case character on the upper row is to be typed, it is merely necessary to then press on the cross piece 51 of the U-shaped key lever 21 to pivot the arms 22 thereof about their pivots 23. As a result, the free ends of arms 22 will move upwardly causing links 24 to be raised to react against the obliquely extending arms 26 of the carriage 27 to pivot the latter in a counterclockwise direction about its pivots 28.

Referring to FIGS. 1 and 3, when the cross piece 33 of locking member is in its lowermost position it will be

in alignment with shoulders 34. Hence the pivots 28 will be retained at the lower end of slots 29 so that the selected character on the upper row of the type wheel will strike the ribbon to cause a corresponding impression to be made on the paper 45.

In the event it is desired to type an upper case character or numeral, it is merely necessary for the shift key 59 to be pressed to pivot the lever 56 in a clockwise direction from the position shown in FIG. 1 to the position shown in FIG. 2. As a result, the hook end of lever 56 will pivot the arms 31 in a counterclockwise direction about the pivots 28 to move the cross piece 33 clear of shoulders 24. Thereupon, with the shift key still pressed, the key lever 21 is pressed which will both move the pivot 28 to the upper end of the inclined slot 29 and rotate the carriage 27.

Since such movement of the pivotal axis of the carriage 27 will cause the arcuate path of movement of the type wheel to change, i.e., to be shifted forwardly, it will cause the selected character on the lower row of the type wheel to strike the ribbon as shown in broken lines in FIG. 2 to make the desired impression. To restore the carriage 27 to normal position, it is merely necessary to release the shift key 59 and the type key 21.

With the relatively simple mechanism above described, a versatile toy typewriter is provided that will afford imprinting of both upper and lower case letters, similar to those on a standard portable typewriter. By reason of the simplicity of the construction above described, the toy typewriter is relatively inexpensive in cost and is capable of long use, without likelihood of derangement.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. In a typewriter mechanism, the combination of a base, a platen structure at the rear thereof, a carriage pivoted on said base on an axis extending parallel to the platen, said carriage having a leg, the pivotal axis for said carriage extending through the end of said leg, a member rising from the base of said typewriter having a downwardly inclined slot through which said pivotal axis extends, an arm pivoted at one end to said pivotal axis and

having an abutment at its other end, a stop normally engaged by said abutment to restrain movement of said arm, thereby retaining the pivotal axis at the lower end of said slot, a type wheel rotatably mounted on said carriage on an axis extending at right angles to the pivotal axis of said carriage, said type wheel having at least two rows of characters thereon positioned one above the other on the periphery of said wheel, means to rotate said carriage about its pivotal axis for movement of the type wheel toward and away from the platen to cause a character on one of the rows to strike the platen, and to urge the pivotal axis of said carriage toward the upper end of said inclined slot, engagement of said stop by said abutment restraining such movement of the pivotal axis, and means to move said abutment away from said stop, whereby when said carriage is rotated about its axis, the arcuate path of movement of the type wheel will be changed and a character on the other of the rows of said type wheel will strike said platen.

5 2. The combination set forth in claim 1 in which said pivoted arm is urged by gravity to position the abutment in engagement with the stop.

10 3. The combination set forth in claim 1 in which the distance from the lower end of said slot to said stop is substantially equal to the distance between the pivotal axis of said arm and said abutment.

15 4. The combination set forth in claim 1 in which the means to move the abutment away from said stop comprises a lever pivotally mounted between its ends and having one end engaging said arm between its ends, and means to rotate said lever to raise the end thereof engaging said arm to pivot the latter about its pivotal mount thereby to move the abutment clear of said stop.

20 5. The combination set forth in claim 1 in which the means to rotate said carriage comprises an actuating arm pivoted between its ends to the base of said typewriter, and a link pivotally connected at its ends to one end of said actuating arm and to the leg of said carriage above its pivotally mounted end, whereby when the other end of the actuating arm is pressed, the end to which the link is connected will move upwardly causing the link to move in corresponding direction to react against the carriage leg, thereby pivoting the carriage against the platen.
